CRIB ATTACHMENT

Edward P. Boehmcke, Brooklyn, N. Y.

Application December 13, 1939, Serial No. 308,909

4 Claims. (Cl. 5—95)

This invention relates to a crib attachment. More particularly, it relates to a folding crib for use as an auxiliary unit in conjunction with a regular bed.

5 An object of the present invention is to provide a simply constructed, relatively inexpensive attachment for a bed to form a crib therewith.

Another object of the present invention is to provide a device of knockdown framework which 10 can be easily assembled and mounted onto a bed frame to form a crib therewith.

One further object of the present invention is to provide a non-slipable attachment for a bed frame, adapted to be knocked down and form a 15 compact portable unit.

Still another object of the present invention is to provide an adjustable attachment adapted to be placed over the mattress of a bed and held in fixed position relative thereto, to form a crib in 20 conjunction with said bed.

Other objects and advantages of the present invention will become apparent from the detailed description of a preferred embodiment, as taken in connection with the accompanying drawing.

25 In the drawing,

Fig. 1 is a perspective view of a preferred form of my crib attachment in connection with a bed.

Fig. 2 is an end view showing details of construction of the attachment as shown in Fig. 1, 30 and

Fig. 3 is a top plan view of a fragmental portion of Fig. 2.

Referring now to the accompanying drawing in which similar reference characters relate to 35 like parts throughout, a bed or cot 10 is provided having a head post 11, a foot post 12 and side rail members 13 and 14. Adapted to fit on cross-rail members, not shown, and forming a part of the bed is a spring upon which rests a mattress 15. It 40 will be noted that the bed is of the ordinary or conventional type and is suitable for the device herein disclosed.

Adapted to be supported upon side rail members 13 and 14, is a knockdown attachment 16 as shown. 45 Said attachment comprises a plurality of vertical post members 17, 18, 19 and 20, preferably of right angular cross section, each post having vertically extending walls 21 and 22 disposed at right angles to each other. The lower terminal 50 portion 23 of each vertical member has part of wall 22 cut away as shown in the drawing, thereby affording a flat abutting surface against side rail members 13 and 14. The wall 21 of said vertical post members is provided with an inwardly extending terminal abutment 24 adapted to slide

against the lower marginal edge of side members 13 and 14. Said abutment 24 is provided with a threaded opening 25 into which fits a flat-headed screw member 26. Said screw member is provided at its free end with a loosely connected pivotal cup-shaped member 27 adapted to contact the lower edge of the side rail members 13 and 14 when the posts are to be fixed thereon as shown in Fig. 1.

Interconnecting post members 17, 18, 19 and 20, 10 is a plurality of rows 28, 29, 30, 31 and 32, respectively, of telescopic members 33 as shown in the drawing. It is to be noted that each row consists of a number of the telescopic members. Posts 17 and 20 being disposed near the head 15 post of bed 10, have a main member 34 in each of the rows thereof pivotally connected to only one wall thereof by means of a pin 35, whereas in posts 18 and 19 a pin 35 is mounted on each of side walls 21 and 22 for each row of telescopic 20 sections. A plurality of successively interconnected telescopic members 36, 37, 38 and 39 are extended from main members 34. Each of the members excepting the main member 34, is flanged at one end 40 thereof while the exposed ends of 25 each member except member 39, are inwardly crimped. This feature permits sliding of the telescopic members without becoming loose from each other or falling apart.

In the above, only a group of members constituting one-half of a row as connected with one of the vertical post members has been described. The above description, however, relates to the other rows as shown in the drawing. Interconnecting each half of the rows of telescopic members between posts 17, 18, 19 and 20 is a sleeve 41, provided with a pair of spaced openings 42 and 43 disposed in alignment with each other. Said openings 42 and 43 are adapted to accommodate the ends of detents 44 and 45, respectively, mounted on the interior of the respective members 39. On the inner face of each of the walls 21 and 22 of the vertical posts there is provided a snap catch 46 adapted to retain the end section 34 of each row, when the members 45 are placed inside each other and the attachment is not in use. The sections of the upper rows when in collapsed position rest on the main member of the succeeding lower row.

In assembling the attachment above described, 50 the telescopic sections are drawn out and away from the vertical posts at right angles to each other and connected at their mid portion by means of sleeves 41. The attachment as a unit is then mounted onto bed 10 so that the lower portions of 55

vertical posts 17, 18, 19 and 20 are in juxtaposition with the respective bed rail members 13 and 14. In order to affix the attachment to the bed rails, screw members 26 on the respective posts are actuated whereby the end 47 of sides 22 of posts 17, 18, 19 and 20 contact the upper edge of the rail and members 27 are held in fixed position against the lower edges of the rails. The attachment rests across mattress 15 and is not easily movable when in a fixed position.

From the foregoing description taken in connection with the accompanying drawing it will be noted that I have provided a bed attachment which is of easy knockdown framework and which 15 can be collapsed into a compact unit particularly for traveling purposes when a regular crib would be too bulky to carry or transport. Furthermore, it is easily attachable to a bed of regular size and affords protection to the child. The attachment 20 does not slip or slide from the bed rails and is adapted to set off a section of the bed for the sole use and comfort of the child. This type of attachment saves the buying of a crib for the child and permits the use of a regular sized bed for 25 the child when it becomes older. Furthermore, the size of the attachment may be varied to meet the needs of various types of beds. Also, the attachment is of rugged, but light and compact construction.

30 While one preferred embodiment of my invention has been described in connection with the accompanying drawing, it is to be understood that various changes as to forms, size, use and arrangement of materials may be made without departing 35 from the spirit and scope of my invention.

I claim:

1. The combination with a bed, of a collapsible crib attachment to form a part thereof, having a plurality of vertical post members of angular 40 cross section, actuatable means at one terminal portion of said posts at spaced intervals thereof for fixing said posts to the bed to form a non-slipable auxiliary portion thereof, a plurality of superimposed rows of telescopic members having one end 45 pivotally connected to said posts, means interconnecting said sections of each row to form a framework with said posts, and means disposed in spaced relationship on said post members for retaining the collapsed telescopic members of each 50 section in fixed position when against said post members.

2. A collapsible crib attachment for a bed and the like comprising a plurality of vertical post members of right angled cross section, each of said posts having a section of a plurality of superimposed rows of collapsible telescopic members in pivotal connection with the post members, the end member of each section being provided with a detent, a sleeve member provided with openings for accommodating the detents of each section of a corresponding row, means on each post for 10 accommodating fastening the telescopic sections when in collapsed condition, and adjustable means at the lower end of each post for fastening the same to the bed.

3. A collapsible attachment, for a bed and the like having a head and foot post, and a pair of side rails intermediate the posts, comprising a plurality of right angled vertical posts adapted to be disposed on the side rails at the head post and at a portion intermediate the head and foot posts, 20 a plurality of superimposed sections of rows of collapsible telescopic members, pivotally connected at one end onto one of the walls of the post members disposed adjacent the head post, a plurality of superimposed sections of collapsible telescopic members pivotally connected at one end to each of the walls of the post members at the intermediate portion on the side rails, intermediate detent means for interconnecting each section in the same row of the respective posts, and 30 adjustable means on each post for fixing the same to the bed rails.

4. A collapsible crib attachment adapted to be affixed to a bed frame to form a part thereof, comprising a plurality of vertical posts adapted to 35 be disposed at spaced intervals on the frame, a pair of said posts being disposed at the head portion of the bed, and another pair being disposed intermediate the ends of the bed frame, said first pair of posts having a plurality of superimposed rows of telescopic collapsible sections pivoted thereto, adapted to be extended toward the second pair of posts, said second pair of posts having a plurality of superimposed rows of telescopic collapsible sections pivoted thereto at right angles 45 to each other and corresponding with the sections of the first pair of posts and with each other, and intermediate detent means for said rows adapted to interconnect the corresponding rows of sections.

50 EDWARD P. BOEHMCKE.
